UNITED STATES PATENT OFFICE

115,269

DESIGN FOR A DRESS

Daniel Novick, Chicago, Ill.

Application February 28, 1938, Serial No. 75,444

Term of patent 7 years

To all whom it may concern:

Be it known that I, Daniel Novick, a citizen of the United States, residing in Chicago, Cook County, Illinois, have invented a new, original, and ornamental Design for a Dress, of which the following is a specification, reference being had to the accompanying drawing forming a part thereof, and in which:

Fig. 1 is a front view of a dress showing my new design; and

Fig. 2 a rear view thereof.

The characteristic feature of my design resides in the combination on the shirtwaist dress disclosed of the specific yokes on the front and back in association with graduated panels of fine tucks on each side of the front opening and the specific blouse back having inverted tucks at the shoulders and waistline producing a pleat-like fullness therein as shown.

I claim:

The ornamental design for a dress, as shown and described.

DANIEL NOVICK.
